CLAIR L. FARRAND, OF FOREST HILLS, NEW YORK, AND ERNEST ROSS, OF EAST ORANGE, NEW JERSEY; SAID ROSS ASSIGNOR TO FARRAND MFG. CO. INC., OF LONG ISLAND CITY, NEW YORK, A CORPORATION OF NEW JERSEY.

LOUD SPEAKER.

Application filed November 5, 1926. Serial No. 146,350.

This invention relates to loud speakers and particularly to that type which employs a large conical diaphragm.

Loud speakers of the cone type as heretofore constructed have included a conical diaphragm, an actuating unit, and a driving rod connecting the actuating unit to the apex of the diaphragm. It has been customary to clamp the apex of the cone between small inner and outer metal caps or washers through which the extremity of the rod passes, and to secure the rod to these caps by means of a set screw. The diaphragms of cone speakers expand and contract considerably, due, among other things, to changes in weather conditions. The expansion and contraction of the diaphragm would give it an undesirable tension and perhaps change the adjustment of the actuating unit if some means were not employed to prevent or overcome this condition. The main advantage of the use of a set screw for clamping the cone to the driving rod resides in the fact that if the diaphragm expands or contracts, the set screw may be momentarily loosened to allow the actuating unit and diaphragm to readjust themselves and reassume their original adjustments, after which the set screw is again tightened. Another advantage of the set screw is that it may be left in a loose condition during shipment of the loud speaker to break the positive connection between the cone and the driving rod so that the jaws to which the speaker is subjected during shipment are less likely to injure the actuating mechanism and the cone. However, the use of a set screw for this purpose has a number of disadvantages. For instance, it is easily lost, it is unsightly, and it constitutes a projection at the apex of the cone which entices persons to turn it bodily around the axis of the driving rod and thereby loosen the metal caps clamped to the apex of the cone.

The principal object of this invention is to provide a loud speaker having an improved type of connecting means at the junction of the driving rod and cone which possess the advantages of the set screw, but which is free of its disadvantages.

One form of the invention is illustrated in the accompanying drawings, in which

Fig. 1 is a side elevation of a loud speaker having the improved connecting means between the driving rod and the apex of the cone.

Fig. 2 is an enlarged sectional view taken on the line 2—2 of Fig. 1, and

Fig. 3 is a detail view showing the clutch member which constitutes one element of the connecting means between the driving rod and the cone.

The loud speaker illustrated in the drawing is of that type ordinarily known as a double cone speaker, but the invention is applicable to any type of loud speaker where it is desirable to connect the diaphragm with a driving rod by clamping means of the type hereinafter described.

The loud speaker illustrated in the drawing comprises a cone-shaped diaphragm 1 and a frustum of a cone 2, the bases of the cone and the cone frustum being united, as by cementing them together. An ornamental cord 3 is placed around the structure so formed at the meeting edges of the cone 1 and cone frustum 2. The edge portion of the cone frustum 2 is held in a ring structure 4 supported by means of rods 5 passing downwardly through an opening in the lowermost portion of the cone structure to a base 6 to which they are secured. The rods 5 support an electrical actuating unit 7 which actuates the driving rod 8 referred to above. A more detailed description of these parts is unnecessary as their construction is immaterial so far as the present invention is concerned.

It is the connection between the driving rod 8 and the cone 1, with which this invention particularly deals, and this connection is applicable to any type of loud speaker, whether of the kind previously described or not.

The improved connection employed between the driving rod and the cone is of the collet and clutch type. The clutch member of the connection is shown in Fig. 3. The clutch member is adapted to be attached to the apex of the cone and for this purpose it is provided with a flange 9 and a threaded extremity 10. The threaded extremity 10 is inserted through a perforation 11 at the apex of the cone and a nut 12 threaded on to

2

the extremity 10 serves to clamp the clutch member to the cone. Before attaching the clutch member to the cone inner and outer metal caps or washers 13 and 14 are applied 5 to the apex of the cone. These caps have central openings corresponding to the perforation 11 in the apex of the cone to permit insertion through them of the end portion 10 of the clutch member. When the nut 12 10 is tightened the apex of the cone, together with the metal caps 13 and 14 are clamped between the nut and the shoulder 9. The clutch member is provided with a central bore or opening 15 to receive the driving 15 rod 8. The bore 15 is slightly larger in diameter than the driving rod. That part of the clutch member to the right of the flange 9 is threaded as shown at 16 to receive a collet 17. This portion of the clutch member 20 is also provided with one or more longitudinal slits 18 extending entirely across the width of the clutch member. In the present instance only one of such slits is employed. It serves to bifurcate the right hand end of 25 the clutch member and to form two resilient jaws which may be pressed inwardly toward the driving rod 8. The extreme end of the clutch member is tapered as shown at 19 and the collet 17 is provided with a tapered opening 20 adapted to cooperate with the tapered extremity on the clutch member in such a way that when the collet 17 is turned in a clockwise direction the resilient jaws of the clutch are wedged or forced inwardly into 30 firm contact with the driving rod 8. This insures a positive and tight connection between the driving rod and the clutch member, and as the clutch member is rigidly attached to the cone, the tightening of the collet 35 establishes a rigid connection from the driving rod to the cone. By turning the collet in the opposite direction, this positive connection is broken, and therefore the collet may be manipulated to establish or break 40 the connection between the driving rod and the cone, thus accomplishing the same result as the above-mentioned set screw heretofore used. The outer surface of the collet 17 is preferably knurled as shown at 21 in 45 Fig. 1, in order that a good grip may be obtained upon it. The collet constitutes convenient and easily manipulated means for momentarily breaking the connection between the driving rod and the cone when it is 50 desired to allow the parts to readjust themselves after expansion or contraction of the diaphragm has taken place. If desired, it may be left in a loose condition during 55 shipment of the speaker, to prevent jars from injuring either the actuating mechanism or the cone. The collet causes the speaker to present a much neater appearance 60 than when a set screw is employed. Furthermore, its exterior surface is smooth, except for the knurling, and there are no pro-

jecting portions with their attendant disadvantages.

Certain details of construction disclosed but not claimed in this application, such for instance as the ornamental cord encircling 70 the periphery of the diaphragm structure; the supporting rods 5 passing through the interior of the cone structure, and the base construction are claimed in various copending applications, the three particular features mentioned being claimed in applications, Serial Nos. 146,347, filed Nov. 5, 1926; 146,348, filed Nov. 5, 1926 and 146,353, filed Nov. 5, 1926.

We claim:

1. A loud speaker comprising a diaphragm, actuating mechanism therefor including a driving rod, and connecting means between the driving rod and the diaphragm comprising a clutch member secured to the 85 diaphragm having resilient jaws, and a collet cooperating with the clutch member adapted, when actuated, to force the resilient jaws of the clutch member into engagement with the driving rod. 90

2. A loud speaker comprising a diaphragm, actuating mechanism therefor including a driving rod, and connecting means between the driving rod and the diaphragm comprising a clutch member secured to the 95 diaphragm, said clutch member having a central opening to receive the driving rod and a plurality of resilient jaws, a member movable longitudinally of the clutch member and means whereby a longitudinal movement 100 of said member causes said jaws to move into or out of engagement with the driving rod.

3. A loud speaker comprising a diaphragm, actuating mechanism therefor including a driving rod, and connecting means between the driving rod and the diaphragm comprising a clutch member provided with a shoulder and a threaded extension to one side at the shoulder, a nut cooperating with 110 said threaded extension to clamp the diaphragm to said shoulder, said clutch member having a central opening to receive said driving rod and being provided at the opposite side of said shoulder with a longitudinal slit to form a plurality of resilient jaws, a collet having threaded engagement with said jaws, and said collet and resilient jaws having interengaging inclined faces whereby turning of the collet causes the resilient jaws to move into or out of engagement with the driving rod. 115

4. A loud speaker comprising a conical diaphragm, actuating means for the diaphragm located at the concave side thereof, 125 said actuating mechanism including a driving rod, and connecting means between the driving rod and the apex of the diaphragm comprising a clutch member secured to the apex of the diaphragm and having a central 130

opening to receive the driving rod, said clutch member having resilient jaws extending outwardly from the apex of the dia- phragm, a collet having threaded engage- ment with said resilient jaws, and said resil- ient jaws and collet having interengaging in- clined surfaces whereby turning of the col- let causes said resilient jaws to move into or out of engagement with the driving rod. In testimony whereof we affix our signa- 10 tures.

CLAIR L. FARRAND.
ERNEST ROSS.
